ELECTRICAL CONNECTOR

James O. Johnson, Lewisberry, Pa., assignor to
Aircraft-Marine Products Inc., Harrisburg, Pa.,
a corporation of New Jersey

Application April 10, 1944, Serial No. 530,313

2 Claims. (Cl. 29—155.55)

1

This invention relates to connectors for insulated electrical conductors, and particularly to terminals for such conductors which are of the type having ferrules designed to be crimped into interlocking and good electrically conductive engagement with the stripped conductor ends.

In electrical terminals of various types provision is sometimes made for holding the insulation against stripping back beyond the part of the conductor that is enclosed within and crimped into interlocking relation to the ferrule of the terminal, such means sometimes comprising insulation clamping ears or jaws stamped up out of the same sheet material of which the terminal connector tongue and the terminal ferrule have been formed.

An object of the present invention is to improve both the construction of terminals of the type just described and to improve their method of application in order to insure a tighter joint between the end of the ferrule and the clamped end of the insulation, whereby to resist the entrance of moisture and other foreign matter into this joint.

Another object of the invention is to simplify the manufacture and reduce the cost of connectors of the type described.

Another object is to facilitate the application of such connectors to the ends of insulated conductors.

To these ends the invention contemplates so spacing the insulation clamping jaws from the ferrule that these jaws may be bodily offset, transversely to the ferrule axis, sufficiently to bring the clamped insulation into concentric or coaxial alignment with the ferrule-enclosed stripped end of the conductor.

Other objects and important features of the invention to which attention has not specifically been directed hereinabove will become apparent when the following description and claims are considered in connection with the accompanying drawings.

Although certain specific examples of this invention and its application in practical use and also certain modifications and alternatives are given herein, it should be understood that these are not intended to be exhaustive or to be limiting of the invention. On the contrary, these illustrations and the explanations herein are given in order to acquaint others skilled in the art with this invention and the principles thereof and a suitable manner of its application in practical use, so that others skilled in the art may be enabled to modify the invention and to adapt it

and apply it in numerous forms, each as may be best suited to the requirements of a particular use.

In the drawings,

Figure 1 is a perspective view of a terminal embodying the present invention, this view showing the terminal before attachment;

Figure 2 is a view in end elevation of a terminal ready for application to a wire, having been formed from the blank of Figure 1; and

Figure 3 is a view in side elevation of an insulated conductor having a terminal embodying the present invention attached thereto.

In the illustrative embodiment of the invention, the terminal is stamped out of sheet metal advantageously relatively pure and therefore not readily machinable copper, for example, high conductivity, oxygen-free electrolytic copper. The connector thus formed comprises a connector tongue 2, which is shown somewhat enlarged at its end and provided with an opening 4 to receive a connecting bolt, not shown; but this tongue is merely representative of the numerous connector devices which can be secured to the end of a conductor; the particular form is not essential to the present invention. A ferrule 6 is formed by rolling up laterally extending wings 5 and 7 to form a cylinder that will fit over the stripped end of the conductor with which the terminal is to be used. Before rolling up the metal to form the ferrule, grooves 9 are preferably formed by impressing that face only of the metal which is to form the inner surface of the ferrule. These grooves and the intervening ribs, extending annularly about the axis of the finished ferrule, serve to provide additional interlock when the ferrule is crimped onto the conductor. The seam 8 formed by the meeting edges of the rolled up material is preferably brazed to prevent spreading of the edges when the ferrule is crimped onto the stripped end of the conductor, as shown in Figure 3, and also seals the joint against ingress of foreign matter and corrosion. This brazing may conveniently be effected in the manner described in the copending application Serial No. 546,835.

The sheet material of which the tongue 2 and ferrule 6 have been formed preferably continues beyond the end of the ferrule remote from the tongue 2 and there is provided with insulation clamping jaws 12 and 14. It will be noted that the jaws 12 and 14 have their ends 16 and 18 tapered toward the opposite sides of the respective jaws so that they will overlap each other smoothly when the jaws are pressed down to embrace and clamp the insulation, as shown in Figure 3.

From an inspection of Figures 1 and 2 it will be seen that, when the terminal is first formed and the ferrule 6 and the clamping jaws 12 and 14 are rolled up from the sheet metal, the center-line of connection both of the jaws 12 and 14 and of the ferrule 6 to the body of the terminal will all lie substantially on a common straight line. If the insulation itself had no thickness this would be the best relation. However, the insulation on conductors with which terminals of this type are used is usually of substantial thickness so that if the jaws were to be closed without offsetting there would be a sharp bend in the central conductor 10 where it is pulled down over the end of the insulation 20 to enter the ferrule 6. This could be compensated and avoided by pre-forming the neck 22 with a bend corresponding to the thickness of the insulation 20, but this adds to the expense of manufacture, and the resulting shoulder interferes with the smooth threading of the wire into the ferrule. Moreover, such a pre-formed terminal is suited only to one thickness of insulation; thus requiring different dies and a separate inventory for every combination of wire size and insulation thickness with each type of terminal tongue.

In accordance with the present invention this neck 22, which connects the jaws 12 and 14 with the ferrule 6 and tongue 2 is of sufficient length so that the jaws 12 and 14 may be bodily offset, transversely to the axis of the ferrule 6, a sufficient distance to bring that part of the conductor 10 which lies within the insulation into coaxial alignment with the ferrule 6 or, in other words, to insure concentric alignment of the clamped insulation and of the ferrule-enclosed stripped conductor end, when the parts are assembled as shown in Figure 3, but it remains flat and aligned with adjacent portions of the ferrule 6 and support 12-14 until after the connector has been assembled on the wire. The required bend in the neck 22 is then formed by the same operation by which the jaws 12 and 14 are closed onto the insulation 20 and the ferrule 6 is crimped onto the bared wire 10.

It will be understood, of course, that the support 12-14 could be offset by pre-forming of the neck 22 before the insertion of the stripped conductor end 10 into the ferrule 6; that is, the terminal may be delivered to the user in this form; but even then by use of my invention the terminals can be re-formed upon application to fit various sizes of insulated wire. Advantageously, however, the offsetting of the support 12-14 is effected simultaneously with the crimping of the ferrule 6 into interlocking engagement with the conductor end 10 and simultaneously with the closing of the jaws 12 and 14 to bring them into clamping engagement with the insulation 20. This may be done by a tool suitably designed for the purpose, such, for example, as that shown in the copending application of Vernon E. Carlson, Serial No. 455,033, filed August 17, 1942, Patent No. 2,359,083.

When applying the connector to an insulated wire, the end is first stripped of its insulation for a distance approximating the length of the ferrule 6. This end is then threaded into the ferrule, which is readily accomplished with my invention by guiding it along the bottom of the channel formed by the support portion 12-14 and the neck portion 22 (best shown in Figure 2). The wire is pushed home so that the edge of the insulation abuts the edge of the ferrule 6. The connector with its wire in place is then placed

between closing and crimping dies as set forth in Carlson Patent No. 2,359,083 and the dies closed.

Since the closing dies for the insulation support and the crimping dies for the ferrule are mounted in fixed coaxial relation, their closing onto the connector automatically bends the neck 22 to effect coaxial alignment of the ferrule and support portions. Moreover, since this bending occurs after the initial closing of the jaws 12-14 onto the insulation it draws the insulation axially closer to the ferrule 6 at the same time that the compression and coining of the ferrule is extruding it longitudinally toward the end of the insulation 20. Thus a tighter joint is formed between the ferrule and insulation which resists entry of corrosion and even tends to resist pressure leakage where the wires pass through pressure bulkheads, etc.

It will be observed that in the closing and crimping operations there is a sequence which follows from the geometrical relations involved. First there is a bending over of the ends 16 and 18 to embrace the wire, these ends being engaged first in the upper die while the lower dies engage only the areas of the ferrule which are to be crimped. The distance of separation, axially, of the opposing pressures results in some bending down of the neck 22 where it joins the ferrule 6. The arcuate, trough-like form of the neck, however, provides stiffness to resist such bending until ends 16 and 18 are closed down and the upper die engages the ferrule at the areas to be crimped. This causes jaws 12 and 14 to reach axially as far as possible along the wire as they are first closed into embracing relation. Near the end of this action the crimping dies engage and begin to flatten the ferrule 6. This flattening causes a further bending down of neck portion 22 as the ferrule is flattened so as to force the conductor 10 to an axial position. Further closing of the dies then compresses the jaws 12 and 14 onto the insulation and compresses and coins the metal of the ferrule and the wire 10 into a solid cross section in the crimped areas, thus lengthening and extruding the ferrule to some extent. At the same time the neck 22 is bent back adjacent the edge of the support portion 12-14 so as to bring this support portion into axial alignment with the ferrule 6; and this results in crowding the support portion with the insulation embraced therein toward the ferrule 6 at the same time that the compression of the jaws 12 and 14 is extruding the insulation toward the ferrule and the coining of the ferrule in the crimped areas is extruding it toward the insulation. All these actions combine to give a tightly compressed end to end joint as well as a mechanically strong engagement and a low resistance stable electrical connection.

From the foregoing description it will be seen that the improved terminal permits such a close and permanent abutting of the clamped insulation 20 against the end of the ferrule 6 and against the shoulder formed by the bending of the neck 22 in the offsetting of the jaws 12 and 14 that a joint between the ferrule end and the insulation is formed and maintained which is substantially impervious to moisture or other foreign matter that might otherwise tend to enter the connection at this point and eventually bring about its destruction.

What is claimed as new is:

1. In the art of attaching an electrical connector to the stripped end of an insulation sheathed electrical conductor, that improvement which includes the steps of: forming from a flat

blank a connector having a tubular ferrule for receiving the stripped conductor end, said tubular ferrule having a closed longitudinal seam, said connector having upstanding, open U-shaped jaws for embracing the insulation sheath adjacent the stripped end and having a substantially straight, narrow intermediate neck integrally connecting the ferrule and jaws; positioning the connector ferrule over the stripped end of the conductor; positioning the upstanding jaws around the insulation sheath adjacent its end, the bight of the U-shaped portion, the neck, and the portion of the ferrule opposite the longitudinal seam being in alignment; and then while the aforesaid portions are in alignment, bending the jaws around and onto the insulation sheath while simultaneously offsetting the neck to bring the insulation sheath and the ferrule into coaxial alignment; and then crimping the ferrule onto the stripped conductor; said bending, offsetting and crimping steps being performed as a part of a single operation.

2. In the art of attaching an electrical connector to the stripped end of an insulation sheathed electrical conductor, that improvement which includes the steps of: forming from a flat blank a connector having a tubular ferrule for receiving the stripped conductor end, said tubular ferrule having a closed longitudinal seam, said connector having upstanding, open U-shaped jaws for embracing the insulation sheath adjacent the stripped end and having a substantially straight, narrow intermediate neck integrally connecting the ferrule and jaws; positioning the connector ferrule over the stripped end of the conductor; positioning the upstanding

jaws around the insulation sheath adjacent its end, the bight of the U-shaped portion, the neck, and the portion of the ferrule opposite the longitudinal seam being in alignment; and then while the aforesaid portions are in alignment, bending the jaws around and onto the insulation sheath while simultaneously offsetting the neck to bring the insulation sheath and the ferrule into coaxial alignment; and then crimping the ferrule onto the stripped end of the conductor and closing the jaws tightly onto the insulation sheath; said bending, offsetting, crimping and closing steps being parts of a single operation.
